C. H. COLLINS

AXMINSTER TUBE FRAME

Filed Oct. 23, 1923

INVENTOR.

Charles H. Collins
BY

Ernest D. Jensen

ATTORNEY.

UNITED STATES PATENT OFFICE.

CHARLES H. COLLINS, OF AMSTERDAM, NEW YORK.

AXMINSTER TUBE FRAME.

Application filed October 23, 1923. Serial No. 670,376.

To all whom it may concern:

Be it known that I, CHARLES H. COLLINS, a citizen of the United States, residing at Amsterdam, in the county of Montgomery 5 and State of New York, have invented certain new and useful Improvements in Axminster Tube Frames, of which the following is a specification.

This invention relates to tube frames for Axminster looms, and the object of this invention is to provide an all metal tube frame of comparatively light weight but of unusual strength and stiffness, and to supply said frame with a number of yarn tubes 15 which are so designed, and attached to the yarn tube supporting member, that they will withstand much heavier strains without becoming distorted or displaced than will any of the yarn tubes such as are now in general use.

The manner in which I accomplish my object is illustrated in the accompanying drawings, in which:

Fig. 1 is a rear elevation, part broken away, of one of my improved tube frames; a tuft yarn spool being indicated by dotted lines.

Fig. 2 is an end elevation of the same.

Fig. 3 is a cross-section along the line 30 3-3 on Fig. 1.

Fig. 4 is a perspective view of one of my improved end yarn tubes.

The same reference characters refer to the same parts throughout the several views.

Referring to the drawings, in which I have illustrated a small or short type of tube frame, A, represents the tube bar which in this case is made of a single piece of sheet metal formed into a tube of substantially the cross-section illustrated, each end having fastened therein a U-shaped end clip D. The clips D, are of less depth than is the tube bar A, and are fastened into the tube bar by welding, or in any other suitable manner.

The channeled form given the top of the tube bar by forming the parallel ribs A², A², in the metal, together with the bead-like interlocking lap or seam A³, adds greatly to the stiffness of the bar and so makes it possible to use a thinner, and therefore lighter metal and still attain the required amount of rigidity. The channel formed in the top of the bar "A" also permits the use of an extra full tuft yarn spool without the increase in diameter interfering with the

proper action of the spool, and without making any change in the relative position of the yarn tubes and the spool center. When producing tube frames for wide Axminster looms wherein the tube bars are not only longer but are required to carry a plurality of tuft yarn spools, I may substitute for the one piece tube bar herein illustrated, such a bar as that shown in U. S. Patent No. 1,452,791 issued to me on April 24th, 1923; or an allowable modification thereof.

The usual frame-carrying chain engaging parts B, and C, are secured to each end of the tube bar. In my improved frame the parts B have formed on the lower end thereof a substantially right angled projection or tongue B², the dimensions of which are such that it will fit with sufficient snugness into the space between the bottom of the U-shaped end clip D, and the lower side of the tube bar. The part B (and the part C), being secured in place by means of screws b and c.

The part B, may be made from strip metal instead of being blanked to a form which will cover or fill the entire end of the tube bar as illustrated, if so desired.

The usual friction spring (or springs) E, adapted to retard the rotation of the tuft yarn spool (or spools), are mounted on the top of the tube bar in any convenient manner.

In my improved tube frame the requisite number of yarn tubes are attached to the tube bar. The individual yarn tubes may be fastened directly to the tube bar, but I prefer to make use of yarn tube units which consist of a plurality of yarn tubes securely attached to a yarn tube carrying angle, said angle being adapted for secure attachment to the tube bar. In my improved frame the two end yarn tubes are preferably of my improved form which has a slightly greater opening therethrough so as to more freely accommodate two tuft yarns, and is provided with a reinforcing rib which so strengthens the tube that it will withstand much heavier strains than will the usual yarn tubes.

Various devices for guarding the ends of a series of yarn tubes from accidental damage have been developed, but have failed to be generally adopted because of the fact that the use thereof necessitated a change in the usual yarn tube threading devices, which change rendered them unavailable for use, without change, when it was desired to

thread up tube frames not provided with like guards.

I attain the same result and to virtually the same extent as do these various guard devices, by strengthening the end yarn tubes of the units in the manner illustrated in the drawings so that they are capable of guarding the rest of the tubes on the unit or frame against accidental distortion or displacement; and without increasing the usual overall length of the yarn tube series.

Reference to the drawings, especially to Fig. 4 thereof, will disclose the manner in which I strengthen said end yarn tubes. The tubes TS, are made from pieces of metal of suitable gage and material cut and formed into tubes of the desired shape which have a rearwardly projecting rib t^2 , the upper end T^3 of which is bent at substantially a right angle thereto and is adapted to be secured to the underside of the tube bar A, or of the tube carrying angle H, to which tubes are frequently attached so as to form a yarn tube unit. The angle H, being adapted for secure attachment to the tube bar proper. By making and attaching the end yarn tubes substantially as shown and described, I provide satisfactory guards for the usual yarn tubes on the frame without making any change which will make necessary a change in the usual yarn tube threading devices which will interfere in any way with the proper handling of present tube frames which are not provided with my improved end tubes or other guards.

What I claim as my invention and desire to secure by Letters Patent is:

1. In a tube frame for an Axminster loom, a tube bar; frame carrying chain engaging members attached at the ends of said tube bar; and a series of yarn tubes projecting from said tube bar, the end tubes of said series having reinforcement and bracing parts so disposed that said end tubes are capable of withstanding a greater force than will the rest of the series.

2. A tube bar for a tube frame for an Axminster loom, comprising a single strip of metal formed into a hollow tube with a channel of substantial depth in the top side thereof, the edges of said strip bent back upon themselves and joined together so as to form an interlocked bead; and end pieces attached inside of and closing the major portion of the opening in the ends of said

tube bar whereby the unclosed portions of said openings form sockets adapted to receive and fit closely a tongue on the chain engaging end brackets.

3. A tube bar for a tube frame for an Axminster loom, comprising a single strip of metal formed into a hollow tube with a channel of substantial depth in the top side thereof, the edges of said strip turned back upon themselves and joined together so as to form an interlocked bead.

4. In a tuft yarn tube for an Axminster tube frame, a metal tube with a rearwardly projecting rib longitudinal thereon, a continuation of said rib projecting sideways therefrom.

5. In a tuft yarn tube for an Axminster tube frame, a metal tube with a rearwardly projecting rib longitudinal thereon, the rear of the upper part of said tube adapted to be secured to the face and the top of said rib to the bottom of the tube carrying member of the tube frame.

6. In a tube frame for an Axminster loom, the combination of a hollow metal tube bar, a clip secured to end of said tube leaving a spaced opening between the wall of said tube and said clip, a chain-engaging end bracket having a single horizontal arm adapted to enter said spaced opening.

7. A tuft yarn tube for a tube frame for an Axminster loom, comprising a piece of sheet metal looped back upon itself, then closed together so as to form a tube with a longitudinal projecting rib thereon, the upper end of said rib bent sideways so as to lie at substantially right angles to the plane of said rib.

8. In a tube frame for an Axminster loom, frame-carrying chain-engaging end brackets, and a one piece hollow tube bar of sheet metal with a channel formed in the top side thereof, said channel comprising spaced integral upstanding flanges and adapted to permit the use of tuft yarn spools of greater diameter by providing greater clearance without change in the relative location of the yarn tubes and the spool center, said sheet metal bar having its longitudinal edges united intermediate the corner edges whereby to form a firm rigid hollow tube bar.

In testimony whereof I have affixed my signature.

CHARLES H. COLLINS.
